THERMOELECTRIC DEVICE

Paul L. Betz, Baltimore, Md., assignor to Consolidated Gas Electric Light and Power Company of Baltimore, Baltimore, Md., a corporation of Maryland

Application March 11, 1946, Serial No. 653,494

22 Claims. (Cl. 175—335).

1

This invention relates to thermoelectrically actuated devices, and more particularly to improved method and means for effecting the actuation of such devices upon the occurrence of predetermined conditions while thermoelectric current is being generated.

Thermoelectrically actuated safety devices are now well known on the market and are frequently used in systems for controlling the fuel supply to burners, these devices being of the type that maintain the fuel valve in open position to permit flow of fuel to the burner as long as a constantly burning pilot flame generates thermoelectric current by heating a thermocouple. On failure of the pilot flame the thermoelectric current decreases due to the cooling of the thermocouple, and the safety device is thereupon actuated to effect the movement of the fuel valve to its closed position and interrupt the fuel supply.

In automatic appliances such as water heaters, means are usually provided to prevent the production of excessive pressures or temperatures within the tank if the control system associated therewith fails to shut off the burner when the proper temperature has been reached, such means commonly including a fusible plug which melts at a given temperature to permit the liquid to flow from the tank or a device employing a pressure relief valve which, upon occurrence of an excessive pressure, opens to relieve the pressure by allowing the contents of the tank to flow out.

It is an object of the present invention to provide, in association with a thermoelectrically actuated safety device, improved means that will respond to excessive temperature or pressure conditions within a heated space, such as a tank, oven, or the like, and cause the actuation of the safety device itself to effect closure of the fuel valve upon occurrence of the conditions deemed dangerous in spite of the fact that the pilot flame is continuing in operation and the thermocouple is therefore generating thermoelectric current and supplying the same to the safety device.

Another object of this invention is to provide a device of the type characterized which may be readily adapted to various forms of thermoelectrically actuated safety devices now on the market.

Another object of this invention is to provide a device of the type characterized which may be readily incorporated in thermoelectrically actuated safety devices that are already installed as well as readily embodied in such devices when manufactured.

Another object of this invention is to provide a

2

device of the type characterized which makes use of alternating current as commonly supplied for lighting purposes.

Another object of this invention is to provide a device of the type characterized which applies to the thermoelectric current generated by the thermocouple of the safety device a superimposed electric current that causes the current in the usual electromagnet or solenoid coil of the safety device to decrease to a value such as to effect the actuation of the safety device.

Another object of this invention is to provide improved means for effecting the actuation of a thermoelectric device upon the occurrence of predetermined conditions notwithstanding that such device is generating thermoelectric current.

Another object of this invention is to provide a device of the type characterized which is simple and compact in structure, easy to install, and certain and efficient in operation.

Another object of this invention is to provide an improved method for operating a thermoelectric device upon the occurrence of predetermined conditions notwithstanding that thermoelectric current is being generated.

Other objects will appear as the description of the invention proceeds.

The invention is capable of receiving a variety of mechanical expressions two of which are illustrated on the accompanying drawings, but it is to be expressly understood that the drawings are for purposes of illustration only, and are not to be construed as a definition of the limits of the invention, reference being had to the appended claims for that purpose.

Referring in detail to the accompanying drawings wherein like reference characters are employed to designate corresponding parts in the several figures:

Fig. 1 is a somewhat diagrammatic elevation of an installation of the present invention as applied to the control of a safety device associated with the burner of a water heater;

Fig. 2 is a fragmentary elevation, partly broken away, of the end of the thermocouple leads associated with the body of the safety device;

Fig. 3 is a vertical section through an embodiment of the present invention;

Fig. 4 is a like view through a second embodiment of the present invention; and

Figs. 5 and 6 are electrical diagrams to illustrate the operation of the embodiments shown in Figs. 3 and 4, respectively.

Referring first to Fig. 1, the invention is shown somewhat schematically as applied to a thermo-

electric safety device applied to the gas burner of a hot water tank, although it is to be expressly understood that the invention is not limited to such an application, but may be applied to thermoelectrically actuated safety devices associated with the heaters of ovens and other enclosures, or to thermoelectrically actuated relays or the like, or in fact wherever it is desired to actuate a thermoelectric device upon predetermined conditions arising while the thermoelectric current is still being generated. As here shown, the tank 10 has a burner 11 supplied with gas or other suitable fuel through pipe 12, valve casing 13 and pipe 14. Leading from the valve casing 13 is a suitable pipe or tube 15 for conveying the fuel to a suitable pilot burner 16 whose flame is indicated at 17. Where automatic control of water temperature is desired a thermostat (not shown) may be applied to tank 10, which controls the flow of fuel through pipe 14 and hence controls the operation of the burner 11.

Installed within the valve casing 13 is a valve having associated therewith a safety device including an electromagnet or solenoid for holding the valve in open position as long as said electromagnet or solenoid is energized by thermoelectric current generated by a thermocouple 18 subjected to the pilot flame 17, as disclosed for example in Patent No. 2,097,838, granted to Sebastian Karrer on November 2, 1937. Such safety device may be of any suitable construction, such, for example as may now be found on the market, and as the details of the safety device constitute no part of the present invention, they have not been illustrated except diagrammatically in Figs. 5 and 6 where the thermocouple 18 is shown as connected by leads 20 and 21 to a coil 22 of an electromagnet or solenoid which would be disposed within the valve casing 13 in operative relationship with the gas valve therein.

In one type of safety device now on the market the casing 13 carries at its upper end an electrical connector 23 provided with a threaded socket and an insulated terminal such as hereinafter described as provided for reception of the terminals of the thermocouple leads in embodiments of the present invention. The thermocouple may be of any suitable construction and, as illustrated in Fig. 2, is shown as having leads of a well known construction now on the market in the form of a metallic tube 24 within which is a concentrically disposed wire 25 provided with insulation to insulate the same from other metal members. The extremity of tube 24 is flared as shown at 26 to engage the lower face of a threaded nut 27. The end of wire 25 has attached thereto a metal disk 28, and interposed between said disk and the flared end 26 of tube 24 is insulation 29. Nut 27 in the present commercial construction is adapted to be threaded into the socket of the connector 23 with the disk 28 in contact with the insulated terminal therein whereby an electrical connection is made with the coil in the casing 13 and thereby the electric circuit from the thermocouple 18 to said coil is completed. While for purposes of illustration the invention has been shown as applied to one form of present commercial thermoelectrically actuated safety device, it is to be expressly understood that the invention is not limited thereto as it can with equal facility be adapted to any suitable thermoelectrically actuated safety device as will be apparent to those skilled in the art.

Referring now to Fig. 3 illustrating one embodiment of the present invention, a metal body

member 30 is provided with an interior chamber 31 which is suitably lined with insulating material, as a fiber liner 32. One end of chamber 31 is closed by a metallic plate 33 suitably held in position, as by screws 34, and the opposite end of said chamber is closed by a plate of insulating material 35 suitably held in position, as by screws 36. At one side said body member 30 carries an electrical connector similar in all respects to the end of the thermocouple leads shown below the line xx in Fig. 2 and comprising an outer metallic tubular member 37 having its end flared at 38 and locked to a threaded nut 39 adapted to be received within the connector 23. Concentrically within said tube 37 is a wire 40 insulated from the tubular member 37 and connected at its end to a metallic disk-like member 41 with insulation 42 interposed between said disk and the end 38 of tube 37. The opposite end of tube 37 is suitably retained, as by brazing or soldering, in a bore hole 43 provided in said body member 30. Body member 30 at its opposite side also carries an electrical connector to receive the thermocouple leads of Fig. 2 and which is identical in all respects with the construction of the connector 23, comprising an interiorly threaded sleeve 44 adapted to receive the nut 27, and a terminal 45 adapted to contact the disk 28 and mounted within a cup of insulating material 46, said terminal 45 being connected to the extremity of the wire 40 opposite the disk 41.

Thus when nut 27 is threaded into sleeve 44 and nut 39 is threaded into connector 23 the disk-like member 28 contacts the terminal 45 and the disk-like member 41 contacts the terminal in connector 23, whereby an electrical connection is established from the wire 25 through wire 40 to one terminal of the coil 22 in casing 13 while tubular lead 24 is in electrical connection with the other terminal of said coil 22 through nut 27, metallic body member 30, tube 37 and nut 39. Thereby the electrical circuit from the thermocouple 18 to the coil 22 in the casing 13 is complete with the interposition of the member shown in Fig. 3 between the terminals of the thermocouple leads and the terminals of the coil leads provided at the connector 23.

In conformity with the present invention means are provided for imposing an alternating current on the aforesaid thermoelectric circuit just described. To this end a wire 47 is suitably attached, as by soldering or brazing, to the wire 40 and at its opposite end wire 47 is suitably attached, as by soldering or brazing, to a lug or connector 48 of any suitable construction mounted on the insulating cover plate 35. A second lug or connector 49 of any suitable construction is mounted on the metallic cover plate 33 and connected by a wire 50 to the metallic body member 30, said wire being electrically attached to lug 49 and body member 30 in any suitable way as by soldering or brazing. Connectors 48 and 49 are connected by leads 51 and 52 (see Fig. 5) to the secondary 53 of a transformer 54. The primary 55 of said transformer is connected by leads 56, 57 and 56' to any suitable source of alternating current such as exist in the usual house lighting mains and indicated by the terminals 58, 58'. Suitably interposed in the circuit composed of the leads 56 and 57 and coil 55 is a switch 59 which may be connected for actuation to any suitable operating means such as a suitable temperature or pressure responsive device. Thus as shown diagrammatically in Fig. 1 the switch 59 is carried

by a member 60 projecting into the interior of the tank 10 where it may be made to respond to either temperature or pressure within said tank so that, upon occurrence of a predetermined temperature or pressure, the switch 59 will be actuated to close the circuit through the coil 55 and, through the operation of the transformer 54, an alternating current will be superimposed on the circuit comprising the thermocouple 18, leads 20 and 21, and coil 22, the alternating current dividing with part flowing through the thermocouple 18 and part through the coil 22 (see Fig. 5). The transformer 54 may be separated physically from or may be mounted on and formed as a unit with body member 30.

Assuming that the pilot 16 is lighted and thermocouple 18 is thus subjected to the heat of the flame, thermoelectric current is generated by said thermocouple and flows to the coil 22 through the electrical connections 25, 28, 45, 40, 41, and the terminal in connector 23, on the one hand, and 24, 27, 44, 30, 31, 39, and the connector 23, on the other hand. As long as this thermoelectric current is generated the coil 22 is energized and the fuel valve in the casing 13 is held in open position. Assume now that for some reason the burner 11 is not shut off when the designed maximum temperature in the tank 10 has been reached. As the thermoelectric current is being generated at the thermocouple 18 the fuel valve is held in open position and will not be actuated by ensuing dangerous conditions. However, when the temperature or pressure in the tank 10, under these assumed conditions, reaches the dangerous condition at which it is desired that the safety device will close the fuel valve, member 60 responds to close the switch 59 and thereby superimpose alternating current through the transformer 54 upon the thermoelectric current flowing in the circuit 18, 20, 21, 22 of Fig. 5. The thermoelectric current is a direct current of predetermined steady value depending upon the construction of the thermoelectric circuit. Under normal conditions when this thermoelectric current decreases in value by a predetermined amount to what may be called the drop value the coil 22 releases the fuel valve so as to effect movement thereof to its closed position. If now the amplitude of the superimposed alternating current passing through coil 22 is greater than the difference between the steady running value and the drop value of the thermoelectric current the superimposed alternating current, compounded with the direct thermoelectric current, will cause the current value to pass through and below the drop value of the current in the circuit including the coil 22, whereby said coil will no longer be able to retain the fuel valve in open position and said valve will be released to close and discontinue the flow of fuel.

The circuit construction of Fig. 3, as shown by the diagram of Fig. 5, employs a parallel arrangement for superimposing the alternating current on the thermoelectric circuit. The present invention may also be embodied in a construction wherein the alternating current is fed to the thermoelectric circuit by a series arrangement as shown in Fig. 4 and illustrated by the diagram of Fig. 6. Referring to Fig. 4, wherein the parts already described in conjunction with Fig. 3 have the same reference characters as in Fig. 3, the body member 30 now is provided with a pair of insulating plates 35 and 35' which carry the lugs or other suitable connectors 48' and 49'. Wire 40 is connected to connector 48' and is provided

with suitable insulation so that it is out of contact with the body member 30, it being shown as passing through a small aperture 62 in the liner 32. In this embodiment, the terminal 45 is connected to the connector 49' by a wire 63 which is also suitably insulated from body member 30. If leads 51' and 52' are now connected to the connectors 48' and 49', following the circuit diagram of Fig. 6, the alternating current in the secondary 53 will be applied to the thermoelectric circuit in series with the thermocouple 18 and the coil 22, and the closure of the valve will occur as heretofore described in conjunction with the embodiments of Figs. 3 and 5.

With the series arrangement, a second transformer, which may also be mounted on or made in unitary relation with the body member 30, is preferably interposed between the secondary 53 and the points of connection of the alternating current circuit to the thermoelectric circuit. As shown in Fig. 6, the circuit of secondary 53 includes the primary 64 of a second transformer 65 whose secondary 66 is connected to the connectors 48' and 49' in the thermoelectric circuit and is in series with the thermocouple 18 and coil 22. The transformer 65 should have a low ratio of transformation, having relatively few turns in the secondary 66, in order that its resistance may be small as compared with the resistance of the coil 22. However, if preferred, the transformer 65 may be omitted and the leads 51' and 52' from coil 53 may be attached directly to the connectors 48' and 49' as previously indicated.

It will therefore be perceived that the present invention provides a simple, compact and easily installed device which may be readily adapted to any suitable form of thermoelectrically actuated safety device for application to such devices as are already installed or for incorporation therein when manufactured, the device providing a temperature or pressure responsive safety feature that will effect the actuation of the thermoelectric safety device itself, notwithstanding that thermoelectric current is being generated, and assure closure of the fuel valve, or the actuation of any other suitable element, upon the occurrence of the predetermined conditions considered dangerous. The invention also provides an efficient means for actuating any suitable thermoelectric device when predetermined conditions arise notwithstanding the generation of the thermoelectric current.

While the embodiments of the invention illustrated on the drawings have been described with considerable particularity, it is to be expressly understood that the invention is not limited thereto as will now be apparent to those skilled in the art. While the invention has been illustrated as applied to a hot water tank it will be apparent to those skilled in the art that it may be applied to any other suitable thermoelectric device that is to be actuated upon the arising of predetermined conditions while thermoelectric current is being generated. While for purposes of illustration the invention has been shown as applied to one known form of commercial thermoelectrically actuated safety device, it will be apparent that the invention can be adapted to any suitable device of this character. Changes may also be made in the details of construction and arrangement of parts, parts illustrated may be replaced by equivalent parts, etc., without departing from the spirit of this invention. Reference is accordingly to be had to the appended claims for a definition of the invention.

What is claimed is:

1. In a thermoelectric device of the type including a thermocouple, a thermoelectric circuit connected thereto and a coil in said thermoelectric circuit, means for superimposing an alternating current of substantially constant value on said coil in said thermoelectric circuit for actuation of said device while thermoelectric current is being generated at said thermocouple comprising a circuit connected to said thermoelectric circuit, a source of alternating current of substantially constant value connected to said second named circuit, and means associated with said source for energizing said second named circuit on the occurrence of a predetermined condition.

2. In a thermoelectric device of the type including a thermocouple, a thermoelectric circuit connected thereto and a coil in said thermoelectric circuit, means for superimposing an alternating current of substantially constant value on said coil in said thermoelectric circuit for actuation of said device while thermoelectric current is being generated at said thermocouple comprising a second circuit connected in parallel to said thermoelectric circuit, a source of alternating current of substantially constant value connected to said second circuit, and means associated with said source for energizing said second circuit upon the occurrence of a predetermined condition.

3. In a thermoelectric device of the type including a thermocouple, a thermoelectric circuit connected thereto and a coil in said thermoelectric circuit, means for superimposing an alternating current of substantially constant value on said coil in said thermoelectric circuit for actuation of said device while thermoelectric current is being generated at said thermocouple comprising a second circuit connected in series with said thermoelectric circuit, a source of alternating current of substantially constant value connected to said second circuit, and means associated with said source for energizing said second circuit upon the occurrence of a predetermined condition.

4. In a thermoelectric device of the type including a thermocouple, a thermoelectric circuit connected thereto and a coil in said thermoelectric circuit, means for superimposing an alternating current of substantially constant value on said coil in said thermoelectric circuit for actuation of said device while thermoelectric current is being generated at said thermocouple comprising a transformer having its secondary connected to said thermoelectric circuit, a source of alternating current of substantially constant value in circuit with the primary of said transformer, and means associated with said source for energizing the circuit of said primary on the occurrence of a predetermined condition.

5. In a thermoelectric device of the type including a thermocouple, a thermoelectric circuit connected thereto and a coil in said thermoelectric circuit, means for superimposing an alternating current of substantially constant value on said coil in said thermoelectric circuit for actuation of said device while thermoelectric current is being generated at said thermocouple comprising a transformer having its secondary connected in parallel to said thermoelectric circuit, a source of alternating current of substantially constant value in circuit with the primary of said transformer, and means in the circuit of said primary for closing said circuit upon the occurrence of a predetermined condition.

6. In a thermoelectric device of the type includ-

ing a thermocouple, a thermoelectric circuit connected thereto and a coil in said thermoelectric circuit, means for superimposing an alternating current of substantially constant value on said coil in said thermoelectric circuit for actuation of said device while thermoelectric current is being generated at said thermocouple comprising a transformer having its secondary connected in series with said thermoelectric circuit, a source of alternating current of substantially constant value in circuit with the primary of said transformer, and means in the circuit of said primary for closing said circuit upon the occurrence of a predetermined condition.

15. 7. In a thermoelectric device of the type including a thermocouple, a thermoelectric circuit connected thereto and a coil in said thermoelectric circuit, means for superimposing an alternating current of substantially constant value on said coil in said thermoelectric circuit for actuation of said device while thermoelectric current is being generated at said thermocouple comprising a transformer having a secondary of few turns and low resistance connected to said thermoelectric circuit, a second transformer having its secondary connected to the primary of said first named transformer, a source of alternating current of substantially constant value in circuit with the primary of said second named transformer, and means in the circuit of said last named primary for closing said circuit upon the occurrence of a predetermined condition.

8. In a thermoelectric device of the type including a thermocouple and a coil in circuit therewith, means for superimposing an alternating current on the coil in said thermoelectric circuit for actuating said device while said thermocouple is generating thermoelectric current comprising a member adapted to be interposed physically and electrically between the terminals of said thermocouple and the terminals of said coil and having pairs of electrical terminals for cooperating with the terminals of said thermocouple and with the terminals of said coil, respectively, said member also having electrical connections in circuit with the aforesaid pairs of electrical terminals adapted to be connected in circuit with a source of alternating current, and a switch associated with said source for energizing said last named circuit on the occurrence of a predetermined condition.

9. In a thermoelectric device of the type including a thermocouple and a coil in circuit therewith, means for superimposing an alternating current on the coil in said thermoelectric circuit for actuating said device while said thermocouple is generating thermoelectric current comprising a metal body member adapted to be interposed physically and electrically between the thermocouple and the coil and provided with terminal connections for one of the leads of the thermocouple and one of the leads of said coil, an electrical connection insulated from said metal member and provided with terminals for connection to the other lead of said thermocouple and the other lead of said coil, a pair of connectors carried by said body member for connection to a source of alternating current and respectively connected to said body member and said electrical connection, and a switch associated with said source for energizing the circuit including said connectors upon the occurrence of a predetermined condition.

10. 10. In a thermoelectric device of the type including a thermocouple and a coil in circuit there-

with, means for superimposing an alternating current on the coil in said thermoelectric circuit for actuating said device while said thermocouple is generating thermoelectric current comprising a metallic body member adapted to be interposed physically and electrically between the thermocouple and the coil and having electrical connections for attachment to one of the leads of said thermocouple and one of the leads of said coil, a pair of connectors having electrical connections for attachment to the other lead of said thermocouple and the other lead of said coil and adapted to be connected in circuit with a source of alternating current, and a switch associated with said source for energizing said last named circuit upon the occurrence of a predetermined condition.

11. In a device for superimposing alternating current on a coil in a thermoelectric circuit for actuation of the latter while thermoelectric current is being generated, a metallic body member provided with electrical connectors adapted to be connected to the thermocouple leads and the coil leads of the thermoelectric circuit, and a pair of connectors carried by said body member for connection with a source of alternating current, said last named connectors being electrically connected with said first named connectors to superimpose the alternating current on the thermoelectric current in said coil when the circuit through said second named connectors is supplied with alternating current.

12. In a device for superimposing alternating current on a coil in a thermoelectric circuit for actuation of the latter while thermoelectric current is being generated, a metallic body member provided with connectors for attachment to a thermocouple lead and a coil lead, an electrical connection carried by said body member for attachment to the other thermocouple lead and the other coil lead, and a pair of connectors carried by said body member and respectively connected electrically to said body member and said connection, said second pair of connectors adapted to be connected with a source of alternating current to superimpose the alternating current on the thermoelectric circuit in said coil when the circuit through said last named connectors is supplied with alternating current.

13. In a device for superimposing alternating current on a coil in a thermoelectric circuit for actuation of the latter while thermoelectric current is being generated, a metallic body member provided with connectors for attachment to a thermocouple lead and a coil lead, and a pair of connectors carried by said body member and having connections carried by said body member for respective attachment to the other thermocouple lead and the other coil lead, said second pair of connectors adapted to be connected to a source of alternating current for superimposing alternating current on the thermoelectric circuit in said coil when the circuit through said last named connectors is supplied with alternating current.

14. In a device for superimposing alternating current on a coil in a thermoelectric circuit for actuation of the latter while thermoelectric current is being generated, a metallic body member provided with connectors for attachment to the thermocouple leads and the coil leads of the thermoelectric circuit, a pair of connectors carried by said body member for connection with a source of alternating current, said last named connectors being electrically connected with said first named connectors to superimpose the alter-

nating current on the thermoelectric current in said coil when the circuit through said second named connectors is supplied with alternating current, and a transformer carried by said body member through which the alternating current is supplied to said last named connectors.

15. In a device for superimposing alternating current on a coil in a thermoelectric circuit for actuation of the latter while thermoelectric current is being generated, a metallic body member provided with connectors for attachment to the thermocouple leads and the coil leads of the thermoelectric circuit, a pair of connectors carried by said body member for connection with a

15 source of alternating current, said last named connectors being electrically connected with said first named connectors to superimpose the alternating current on the thermoelectric current in said coil when the circuit through said second named connectors is supplied with alternating current, and a transformer carried by said body member and connected in parallel through said last named connectors with said thermocouple and coil leads.

25 16. In a device for superimposing alternating current on a coil in a thermoelectric circuit for actuation of the latter while thermoelectric current is being generated, a metallic body member provided with connectors for attachment to the

30 thermocouple leads and the coil leads of the thermoelectric circuit, a pair of connectors carried by said body member for connection with a source of alternating current, said last named connectors being electrically connected with said first named connectors to superimpose the alternating current on the thermoelectric current in said coil when the circuit through said second named connectors is supplied with alternating current, and a transformer carried by said body

40 member and connected in series through said last named connectors with said thermocouple and coil leads.

45 17. The method of actuating a thermoelectric device upon the occurrence of a predetermined condition notwithstanding the generation of thermoelectric current which includes the step of imposing on the thermoelectric circuit an alternating current the peak value of which is substantially constant and is greater than the difference between the steady running value of the thermoelectric current and the current value at which the thermoelectric device is operated upon decrease in the generation of thermoelectric current.

55 18. The method of operating a thermoelectric device to cause said device to function on a predetermined condition notwithstanding the continued generation of thermoelectric current which comprises connecting the thermoelectric

60 circuit which includes a thermocouple and an electromagnet winding with a source of alternating current the peak value of which is substantially constant and is greater than the difference between the steady running value of the

65 thermoelectric current and the current value at which the device is actuated upon decrease of the thermoelectric current to compound the alternating and thermoelectric currents and cause the current in the said electromagnet winding to decrease below said last named value upon the occurrence of said predetermined condition.

70 19. In a thermoelectric device of the type including a thermocouple adapted to be subjected to a source of heat and a device including a coil in circuit with said thermocouple adapted to

operate upon a predetermined decrease in the thermoelectric current generated at said thermocouple, means for actuating said device while said thermocouple is generating thermoelectric current including means adapted to be interposed physically and electrically between the thermocouple and the coil for connecting a source of alternating current to the coil in said thermoelectric circuit and a switch for closing said circuit including said source of alternating current to superimpose the alternating current on the thermoelectric current in the coil in said thermoelectric circuit, said switch being provided with means responsive to the occurrence of a predetermined condition.

20. A device for connecting the thermocouple and solenoid coil of a thermoelectric safety device comprising a body member having elements forming terminals for one of the leads of the thermocouple and one of the leads of the coil, said terminals being electrically connected to one another, means carried by and insulated from the terminal-forming elements of said body member and forming electrically connected terminals for connection to the other lead of said thermocouple and the other lead of said coil, a pair of connectors carried by said body member for connection to a source of alternating current, and means for electrically connecting one of said pair of connectors to one of the leads of the thermocouple and the other connector to one of the leads of the coil.

21. A device for connecting the thermocouple and solenoid coil of a thermoelectric safety device comprising a metallic body member having elements forming terminals for one of the leads of the thermocouple and one of the leads of the coil, said terminals being electrically connected to one another through said body member, a

conductor housed within and insulated from said body member and having terminals for connection to the other lead of said thermocouple and the other lead of said coil, a pair of connectors carried by said body member for connection to a source of alternating current, one of said connectors being insulated from said body member and the other being electrically connected thereto, and means for electrically connecting said insulated connector to said conductor.

22. A device for connecting the thermocouple and solenoid coil of a thermoelectric safety device comprising a metallic body member having elements forming terminals for one of the leads of the thermocouple and one of the leads of the coil, said terminals being electrically connected to one another through said body member, means carried by and insulated from said body member forming terminals for connection to the other lead of said thermocouple and the other lead of said coil, a pair of connectors carried by and insulated from said body member for connection to a source of alternating current, and means for electrically connecting said pair of connectors to the terminal-forming means carried by said body member.
